LIPSTICK HOLDER AND LIPSTICK

Albert E. Vaughn, Orange, N. J.

Application January 14, 1946, Serial No. 641,062

8 Claims. (Cl. 132—79.3)

1

This invention relates to toilet accessories and particularly to cosmetic dispensers of a type in which lipstick or the like is contained within a receptacle and dispensed therefrom as required.

Various types of cosmetic dispensers and applicators are now in use, one form consisting of a barrel for holding lipstick or the like and provided with a longitudinal slot through which projects the finger piece of a feeding element slidably arranged within the barrel and engaging the lower end of the lipstick to force the latter upwardly. Another type of holder comprises a lipstick receptacle provided with a helical slot for receiving the lug of a propelling element which is carried by a receptacle within the container and has an opening through which the lug extends to engage in the helical slot, relative rotation between the receptacle and container causing the propelling element to move longitudinally to feed the lipstick outwardly.

It has been determined that more efficient use of the lipstick can be obtained if its end is beveled. However, the use of such lipsticks presents a serious problem inasmuch as the top thin edge of the lipstick wears down faster than the remaining portion and thus there is a tendency for the lipstick to build up at the lower side of the inclined end to not only defeat the purpose of the slanted end but cause malformation of the lipstick and spreading of the built-up surplus over the side of the container to soil the fingers of the user. Moreover, since previous devices have no means for supporting the sides of the upper projecting end of the lipstick, the latter is apt to bend and break during use. Furthermore, such lipstick holders are non-refillable and must be discarded when the supply of lipstick has been depleted.

The present invention was conceived as a means for obviating the above outlined faults of prior cosmetic dispensers and it is one object to provide a holder of the type indicated having a lipstick receptacle provided with a removable lower end to adapt a fresh supply or refill to be inserted therein.

Another object is to provide a lipstick holder having a member attached to the lipstick and slidably within the receptacle, and an operating ring engaging the member and having a threaded engagement with the receptacle whereby to cause the lipstick to be fed in either direction upon relative rotation between the ring and receptacle. This is important as it permits retraction of the lipstick into the receptacle when not in use.

2

Another object is to provide a lipstick holder in which the upper end of the lipstick barrel is beveled to conform to the inclination of the end of the lipstick whereby to properly support the sides of the latter to prevent damage thereto.

Another object is to provide a lipstick holder in which the barrel is formed with a bore of substantially ovate shape for containing lipstick of similar cross section thereby providing that the uppermost portion of the lipstick, or that part adjacent its relatively thin edge, will have a greater area than the lower portion of its sloping surface whereby to compensate for the normal faster wearing away of the lipstick at the tip and cause the lipstick to wear away more evenly and avoid the tendency toward building up on the lower side of the beveled end.

Another object is to provide a cosmetic dispenser which, because of the peculiar formation of the upper end of its barrel eliminates waste of the lipstick and thereby requires less adjusting than previously used devices of similar types.

Another object is to provide a cosmetic dispenser composed of a minimum number of parts adapted for economical manufacture on a production basis and easily assembled without the exercise of special skill or use of tools, and one which is durable and highly efficient in performing its intended function.

Another object is to provide an applicator stick of ovate cross section and having a beveled end with the vertex of the bevel arranged adjacent that portion of the ovate contour of greatest area whereby to compensate for the normal faster wearing away of the stick at the tip.

Further objects of the invention are set forth in the following specification which describes two preferred forms of construction of the device, by way of example, as illustrated by the accompanying drawing. In the drawing, which is for illustrative purposes only:

Fig. 1 is a longitudinal sectional view through a preferred form of cosmetic dispenser constructed in accordance with the present invention;

Fig. 2 is a side elevation thereof, shown part-sectional on line 2—2 of Fig. 1;

Fig. 3 is a top plan view of the same;

Fig. 4 is a cross-sectional view, taken on line 4—4 of Fig. 1;

Fig. 5 is a side elevational view of a modified form of cosmetic dispenser, shown part-sectional to illustrate its internal elements;

Fig. 6 is a top plan view of the device shown in Fig. 5; and

Fig. 7 is a cross-sectional view taken on line 1—7 of Fig. 5.

The present improved cosmetic dispenser preferably comprises, in general, an externally threaded lipstick receptacle or barrel provided with a chamfered end and longitudinal opening, removable closure means for the other end of the barrel, a cup-shaped slide element attached to the lower end of the lipstick to slide within the barrel and provided with a portion engageable in the opening of the barrel, and an annular member engaged with the threads of the barrel and connected to the slide element whereby relative rotation between the barrel and annular member in either direction will feed the lipstick longitudinally to project its end beyond the barrel or withdraw it thereinto.

Referring first to Figs. 1 to 4 of the drawing, the preferred form of the device includes a sleeve-like receptacle or barrel 10 formed on its periphery throughout the greater portion of its length with screw threads 11. The barrel 10 has a longitudinal slot or opening 12 extending from its lower end to a point adjacent its upper end. An axial bore 13 extending through the barrel 10 is substantially ovate shape in cross section, as indicated in Figs. 3 and 4. That is to say, the bore 13 has a substantially semi-circular portion 14, a diametrically-opposite portion 15 of greatly reduced radius, and curved connecting portions 16 of relatively large radius. The upper end of the barrel 10 is beveled as indicated at 18 with the highest portion or tip of the bevel arranged adjacent the portion 14 of the bore 13 and the lowest part of the bevel positioned at the portion 15 of the bore.

The lower end of the receptacle 10 is normally closed by a cap or closure member 20 having an outer upstanding annular flange 21 provided with screw threads 22 on its outer periphery. A second inner annular flange 23, similar to the flange 21 is also provided, thus forming an annular groove 24 therebetween for receiving the lower end of the barrel 10. In order to frictionally hold these two parts in assembled relationship the inner flange 23 is slotted at spaced intervals to provide resilient fingers 25 adapted to grip the interior of the barrel. A lug 26 formed between the two flanges 21 and 23 is adapted to enter the lower end of the slot 12 of the barrel to key the barrel and closure member 20 together to prevent relative rotation therebetween.

Slidably mounted within the bore of the barrel 10 is a cup-shaped element 30 in which the lower end of the lipstick 27 is placed and suitably held. As shown in Figs. 1 and 2, the slide element 30 is provided with a lug 31 which projects outwardly through the slot 12 of the barrel 10. The lug 31 is slotted as shown at 32 to receive an annulus or ring 33. The ring 33 is provided with internal screw threads 34 which engage with the external threads 11 of the barrel 10, so that relative rotation between the barrel and ring will cause the slide element 30, together with the lipstick 27, to be slid axially to project or withdraw the lipstick, depending upon the direction of such rotation.

To assemble the parts of this device the slide element 30 with its attached lipstick 27 is first slid into the lower end of the receptacle 10. During this assembly the ring 33 is placed over the end of the barrel and positioned within the slot 32 of the member 30, after which the ring is turned to thread it onto the barrel. With the operating elements thus assembled, the lower end of the

barrel 10 is sealed by the cap 20 which is placed thereover to cause its fingers 25 to frictionally hold it in place. When it is desired to refill the device the cap 20 may be forced off from the end 5 of the barrel and the ring 33 unscrewed from the barrel to release the slide element 30 which may be replaced by a new element and fresh lipstick and the parts reassembled in the manner above explained. It will be noted, however, that the 10 same slide element may be reused, provided that the remaining lipstick is removed therefrom and the fresh lipstick forced into its interior. As is common in lipstick holders, a cylindrical cover may be employed for enclosing the barrel, the present drawing indicating such a removable cover by dot-and-dash lines and the reference character 28 in Fig. 1. As shown, the cover 28 may have screw threads to adapt it to be screwed onto the external threads of the cap 20.

To use the lipstick the ring 33 is turned sufficiently to raise the lipstick slightly, say one-sixteenth of an inch above the upper end of the barrel, after which it may be applied to the lips in the usual manner. As previously explained, a 20 more even distribution of the cosmetic is obtained by beveling the end of the stick. In the present improved holder, the upper end of the barrel is cut at an angle to provide a combined support and guard for the projecting end of the lipstick. In addition, the slanted end of the barrel being 25 at a relatively short distance from the end of the lipstick controls and maintains the latter at the proper angle. As an important feature of improvement, the lipstick barrel is provided with an 30 ovately-shaped bore which, combined with the inclination at its upper end, maintains a greater area of cosmetic adjacent the tip or vertex of the lipstick to insure even application thereof to the lips and prevent the building up of a surplus at the lower portion of the chamfer. If the entire 35 amount of lipstick which projects beyond the end of the barrel is not used during one application, this end may be withdrawn into the barrel by merely turning the ring 33 to cause the slide element 30 to move downwardly. Following an application of lipstick the cover 28 may be placed over the open end of the barrel 10 and screwed onto the cap 20 as indicated in Fig. 1.

Figs. 5, 6 and 7 illustrate a lipstick holder embodying a slightly modified type of construction. In this device the lipstick receptacle or barrel 35 is provided with diametrically opposite longitudinal slots 36 extending throughout the greater portion of its length and with a peripheral flange 55 37 adjacent its inclined upper end 38. A cap or closure member 39, similar to the cap 20 shown in Figs. 1 to 4 is employed for closing the lower end of the barrel 35. A slide element 41 is slidably mounted within the barrel 35 and has a recessed 60 upper end 42 for receiving the lower end of the lipstick 40. The slide element 41 also has opposite radial lugs 43 which project outwardly through the slots 36 of the barrel 35 and into helical cam grooves 44 formed on the interior of an outer barrel or operating sleeve 45. As shown in Fig. 5, the sleeve 45 is held axially in place between the flange 37 of the barrel 35 and the cap 39. Thus 65 it will be seen that relative rotation between the inner and outer barrels 35 and 45 will cause the slide element 41 and lipstick 40 to be moved axially in either direction, depending on the direction of relative rotation, the long lead of the helical grooves 44 effecting rapid movement of the lipstick.

70 It will be observed from the foregoing that the

present invention provides a simple yet ingenious lipstick holder incorporating novel features of improvement not present in similar cosmetic dispensers of previous types. For example, through the improved construction the lipstick can be quickly and conveniently projected and retracted as required. Moreover, by beveling the upper end of the receptacle or barrel which has an ovately-shaped bore, the end of the lipstick will be maintained at the desired angle and its upper edge or tip, which usually wears down at a greater rate, will have a larger area than the lower portion of its sloping surface thereby insuring a more even distribution of the cosmetic to the lips. Because the sides of the lipstick are suitably supported by the barrel throughout its entire length, the tendency of the lipstick to break or bend during use is entirely eliminated. As an added feature of improvement the lower end of the receptacle is closed by a cap which is merely snapped on, thus eliminating costly and complicated fastening means. The parts of the device may be made from any suitable material such as plastics to afford a pleasing appearance and are easily and quickly assembled without the use of tools or the exercise of special skill.

Furthermore, the present invention provides a novel form of lipstick and the like for use in the improved holder herein described or in other types of holders and dispensers. The improved applicator stick which is of ovate cross section has at least one beveled end with the vertex of the bevel arranged adjacent that portion of the ovate contour of greatest area to compensate for the normal faster wearing away of the stick at the tip.

While the improved cosmetic dispenser and lipstick have been herein shown and described as embodied in preferred forms of construction by way of example, I do not intend to be limited to the specific disclosure contained herein since various changes, modifications, and substitutions may be incorporated in the exemplary embodiments disclosed without departing from the spirit of the invention, and I hereby reserve the right to all such changes, modifications, and substitutions as properly come within the scope of my appended claims.

I claim as my invention:

1. A cosmetic dispenser, including: a lipstick receptacle having an ovately-shaped bore throughout its length for receiving a lipstick of similar cross section and having an obliquely beveled end, the vertex of the bevel being arranged adjacent that portion of the ovate bore of greatest area; and means for feeding said lipstick outwardly beyond said beveled end of the receptacle to adapt it to assume the slope of said beveled end when applied to use.

2. A cosmetic dispenser, including: a receptacle having an ovately-shaped bore for containing a lipstick or the like of similar cross section, and having an obliquely beveled end, the vertex of the bevel being arranged adjacent that portion of said ovate bore of greatest area; an element slideable within said bore and adapted to be joined to the inner end of the lipstick for moving same; and means movable on the receptacle and connected to said element for sliding the latter and the lipstick longitudinally.

3. A cosmetic dispenser, including: a receptacle having a bore of ovate outline for containing a lipstick or the like of similar cross section and having an obliquely beveled end, the vertex of the bevel being arranged adjacent that portion of the ovate bore of greatest area; an element slid-

able within said bore and adapted to be joined to the inner end of the lipstick for moving the same; an operating member surrounding said receptacle and connected to slide said element; and cooperating means on said member and receptacle operative upon relative rotation therebetween to feed said element and lipstick longitudinally.

4. A cosmetic dispenser, including: a receptacle for containing a lipstick or the like and having a screw-threaded exterior and a bore of ovate outline, one end of said receptacle being beveled obliquely in one direction with the vertex of the bevel arranged adjacent that portion of said ovate bore of greatest area, said receptacle having a longitudinal opening therein; means for closing the opposite end of said receptacle; a cup-shaped element slideable in said receptacle and adapted to be joined to the inner end of the lipstick, said element being provided with a lug projecting through said opening of the receptacle; and an annular member surrounding said receptacle and connected to said element, said member being provided with screw threads engageable with those on the receptacle whereby relative rotation between said member and receptacle in one direction causes the element to feed the outer end of the lipstick beyond the beveled end of the receptacle for application and rotation in the opposite direction withdraws the lipstick.

5. A cosmetic dispenser, including: a receptacle having a bore of ovate outline for containing a lipstick or the like of similarly shaped cross section and having an obliquely beveled end, the vertex of the bevel being arranged adjacent that portion of the ovate bore of the greatest area, and having a longitudinal opening therein; helical threads on the exterior of said receptacle; an element slideable within said receptacle and adapted to be joined to the lipstick, said element being provided with a lug projecting through said opening in the receptacle; and a member surrounding said receptacle and connected to said element, said member being provided with helical threads engageable with those of said receptacle whereby relative rotation between said receptacle and member causes said element to move the end of the lipstick longitudinally beyond the beveled end of the barrel and to withdraw it into said receptacle, depending upon the direction of such rotation.

6. A cosmetic dispenser comprising: a receptacle for containing a lipstick or the like; and means for feeding said lipstick beyond the end of the receptacle for use, said receptacle having a bore of ovate outline throughout its length and an obliquely beveled end, the vertex of the bevel being positioned adjacent that portion of the ovate bore of greatest area, and said bore and bevel cooperating to evenly dispense the lipstick throughout the entire area of the bevel.

7. A cosmetic dispenser, including: a receptacle for containing a lipstick or the like and provided with external helical threads; an element slideable in said receptacle and joined to the lipstick; and operating means connected to said slideable element and engageable with said helical threads for feeding said element and lipstick longitudinally upon relative rotation between said receptacle and operating means.

8. A cosmetic dispenser, including: a receptacle for containing a lipstick or the like, said receptacle being provided with a bore of ovate shape and a beveled end with the vertex of the bevel arranged adjacent that portion of said ovate bore of greatest area, and having longitudinal open-

ings therein; a peripheral flange on said receptacle adjacent its beveled end; a removable cap for closing the other end of said receptacle; an element slidable within said bore and adapted to be joined to the lipstick, said element being provided with lugs projecting through said opening; an operating member rotatable on said receptacle and positioned between said flange and said cap; and helical grooves in said operating member engageable with said lugs and operative upon relative rotation between said member and said receptacle to feed said element longitudinally outward to project the lipstick beyond the beveled end of said receptacle and to draw it thereinto, depending upon the direction of such relative rotation.
